(57) **CLAIM**

The ornamental design for a grilling apparatus, as shown and described.

DESCRIPTION

The patent or application file contains at least one drawing executed in color. Copies of this patent or patent application publication with color drawing(s) will be provided by the Office upon request and payment of the necessary fee.

2. Grilling apparatus

2.1 is a front perspective view of a grilling apparatus showing our new design;

2.2 is a top, front, and right side perspective view thereof; and

2.3 is a rear perspective view thereof.
